EX

D7463

OR D 11,472

UNITED STATES PATENT OFFICE.

JOHN V. B. CARTER, OF CINCINNATI, ASSIGNOR TO MYERS, OSBORNE & CO., OF CLEVELAND, OHIO.

DESIGN FOR STOVES.

Specification forming part of Design No. **11,472**, dated October 28, 1879; application filed August 25, 1879.
[Term of patent 7 years.]

To all whom it may concern:

Be it known that I, JOHN V. B. CARTER, of Cincinnati, in the county of Hamilton and State of Ohio, have originated and designed a Fanciful Shape and Exterior for Stoves, of which the following is a full, clear, and exact description, reference being had to the accompanying illustration, making a part of this specification.

A represents the hearth-section, B the grate-section, and C the combustion-chamber section, of the stove. The grate-section and combustion-chamber are separated by a ledge, D, while at the right and left front corners are represented pillars of suitable shape. The grate-section B is embellished with a fanciful door, B', upon its front. So also the combustion-chamber section is embellished with a door, C', at its side, and with a fanciful seal, C², in front. The seal is of spade form. The hearth-section has a fanciful rail, E. I prefer, generally, to plate the surfaces of the rail E and portions of the pillars, doors, and seal with yellow or white metal.

The stove-top is provided with two concentric rims, F and F', the outer one, F, inclosing the inclined or raised portion G, while the inner one, F', incloses the urn H. The end door, C', is provided in its central portion with

mica windows a, while its upper portion is provided with an ornamented portion, b, and its lower portion with the oblong horizontal plate c, having a number thereon. The spade-shaped seal C² has the words "Golden Star" thereon.

What I claim is—

1. In a design for heating-stoves, the combination, with the outer rim, F, inclosing the raised top portion, G, of the concentric inner rim, F', inclosing urn H, substantially as set forth.

2. In a design for heating-stoves, the end door, C', having central mica windows a, upper ornamental portion, b, and horizontal oblong plate c on its lower portion, substantially as set forth.

3. In a design for heating-stoves, the combustion-chamber section C, provided with the spade-shaped seal C² on the front central portion thereof, substantially as set forth.

In testimony whereof I have signed my name to this specification in the presence of two subscribing witnesses.

JOHN V. B. CARTER.

Witnesses:

C. G. HINE,
J. WM. JOHNSON.
